UNITED STATES PATENT OFFICE.

EDWARD A. TAYLOR, OF CLEVELAND, OHIO, ASSIGNOR TO THE GRASSELLI CHEMICAL COMPANY, OF CLEVELAND, OHIO, A CORPORATION OF OHIO.

PROCESS OF DISSOLVING SODIUM SILICATE.

1,341,288.

Specification of Letters Patent. Patented May 25, 1920.

Application filed October 10, 1917. Serial No. 195,708.

To all whom it may concern:

Be it known that I, EDWARD A. TAYLOR, a citizen of the United States, and a resident of Cleveland, county of Cuyahoga, and State 5 of Ohio, have invented a new and useful Improvement in Processes of Dissolving Sodium Silicate, of which the following is a specification, the principle of the invention being herein explained and the best 10 mode in which I have contemplated applying that principle, so as to distinguish it from other inventions.

The subject of the present application is a method of treating a solid material with a 15 liquid, either for the purpose of securing a suspension of the former in the latter or for dissolving the solid in the liquid, the present description referring particularly to one application of this method to the dissolving of 20 sodium silicate, together with a preferred form of apparatus for carrying out this method.

Commercial sodium silicate, which is ordinarily prepared by the fusion of silicious 25 and alkaline materials in a suitable furnace, is a solid material which is practically insoluble in water at ordinary temperatures and under ordinary conditions. For use in 30 various arts it is necessary, however, to dissolve sodium silicate in water, and considerable difficulty has been experienced in effecting this solution on a commercial scale. In fact, it may be said that this has been 35 accomplished commercially only by the employment of comparatively intricate processes, which involve the use of complicated and expensive machinery.

One object of the present invention is a 40 provision of a method of dissolving sodium silicate in water without the use of complicated or expensive machinery and without the use of expensive means of agitating the body during its dissolution. To the accomplishment of the foregoing and related ends, 45 said invention, then, consists of the means hereinafter fully described and particularly pointed out in the claims.

The annexed drawing and the following 50 description set forth in detail certain means and one mode of carrying out the invention, such disclosed means and mode illustrating, however, but one of the various ways in which the principle of the invention may be used.

For convenience and clearness of description I will preferably describe my improved method in connection with an improved form of apparatus, which is shown in the accompanying drawings. In said annexed drawings:-

Figure 1 is a transverse vertical section showing certain parts and connections in elevation; Fig. 2 is a plan view of the apparatus shown in Fig. 1; and Fig. 3 is a side elevation of the upper end of the apparatus, 65 together with the connections.

Referring now to Fig. 1, there is shown a suitable supporting frame 1, upon which is mounted a substantially cylindrical chamber 2 arranged in a vertical position and having a curved bottom 3 upon which there is mounted in suitable bearings an agitating screw 4, which is held at its upper end in a yoke 5 suitably attached to the top or cover 6 of the cylinder. This agitating screw 4 is 70 inclosed in a cylindrical casing 7, which terminates short of the lower and upper end of the agitator and is open at both ends to the interior of the chamber 2. The agitator is driven by means of a shaft 8 extending 75 through the cover 6 and bearing a gear 9 driven by a gear 10 on a driving shaft 11.

Mounted adjacent to the bottom 3 of the cylinder is a screen or grille 12 extending horizontally across the cylinder and serving 80 to support the charge of silicate or other material when it is introduced into the chamber. This grille 12 is suitably supported upon brackets 13 attached to the walls of the cylinder 2. In the top 6 there is an opening 90 which is normally closed by means of a man-hole cover 14, and through this opening the charge of silicate is first introduced into the apparatus. Also extending through the cover 6 are two conduits 15 and 16, the first 95 conduit being connected to a coil 17 disposed in the chamber 2 adjacent to the walls of the same. This coil 17 is provided with a drain pipe 18 extending through the side of the chamber and is adapted to have steam pass 100 therethrough during the operation of the apparatus. The other of the two conduits, 16 discharges directly into the chamber 2 and is provided with connections 18, 19 and 20, controlled by valves 18', 19' and 20', 105 which are adapted to carry water, steam and air respectively. The bottom of the cylinder 2 is similarly provided with a drain

pipe 21 controlled by means of a valve 22 for removing the liquid contents of the cylinder after each operation.

Assuming now that a charge of sodium 5 silicate is to be dissolved according to my improved method, the solid material is first charged into the chamber to a point below the top of the cylinder 7 around the agitator 4. Water is then run into the chamber 2 10 through the pipes 18 and 16 to any desired level, which will be adjacent to the top of the cylinder, after which the manhole is closed by the cover 14 and retaining means for the same firmly secured. Steam or other 15 heating medium is then caused to circulate through the closed coil 17 until the pressure generated on the inside of the apparatus by the heat of this coil is within a few pounds of the pressure of the steam itself, and suitable gages may be connected to the steam 20 inlet pipe 15 and to the interior of the chamber 2 for determining these relative pressures. During this heating of the contents of the chamber 2 the agitator is run 25 either continuously or intermittently a sufficient amount to provide a slow circulation of the material through the chamber 2 and thus thoroughly mix the water and solid matter therein. This agitation prevents the 30 settling and accumulation of any impurities at the bottom of the machine as well as the formation of lumps which prevent free access of the solution to the solid material. The formation of lumps slows down the dissolving of the material and prevents accurate samplings of the contents of the apparatus.

After the pressure in the chamber 2 has been brought to approximately the pressure 40 of the steam in the coil 17, steam, or some other heating medium which is inert to the sodium silicate, is introduced through the lines 19 and 16 and thus brought directly in contact with the water and the sodium silicate suspended or dissolved therein. During 45 this action of the steam on the contents of the chamber 2, which again raises the temperature of the materials therein, the agitator is operated sufficiently to provide the proper circulation of the materials through 50 the chamber. This operation is continued until samples taken from the discharge pipe 21 show the degree of concentration desired, when the solution is drawn off through that 55 connection, leaving in some cases undissolved

material on the grille 12. This residue is of course treated in the next batch, and in ordinary operation it is not expected that one charge will be entirely dissolved at any one time, it being necessary ordinarily to 60 add about one-third of the original charge after each operation as this gives satisfactory concentration of the solution.

Other modes of applying the principle of my invention may be employed instead of 65 the one explained, change being made as regards the method herein disclosed, provided the step or steps stated by any of the following claims or the equivalent of such stated step or steps be employed.

I therefore particularly point out and distinctly claim as my invention.

1. In a method of dissolving a soluble silicate, the steps which consist in passing a solvent over and through an excess of soluble 75 silicate and heating such solvent with a gas chemically inert to such soluble silicate.

2. In a method of dissolving a soluble silicate, the steps which consist in acting upon a large excess of soluble silicate with 80 a solvent, maintaining such soluble silicate in a quiescent condition and passing such solvent gently through the same and heating such solvent during such passage.

3. In a method of dissolving a soluble 85 silicate, the steps which consist in acting upon a large excess of soluble silicate with a solvent, maintaining such soluble silicate in a quiescent condition and passing such solvent gently through the same and heating 90 such solvent during such passage with a gas chemically inert to such soluble silicate.

4. In a method of dissolving a soluble alkaline silicate or the like, the steps which consist in heating an excess of soluble silicate 95 in the presence of water with steam, maintaining such soluble silicate in a quiescent condition and slowly forcing such water through such soluble silicate.

5. In a method of dissolving a soluble 100 alkaline silicate or the like, the steps which consist in heating an excess of soluble silicate in the presence of water with steam, maintaining such soluble silicate in a quiescent condition, slowly forcing such water through 105 such soluble silicate, and then drawing off the solution when the required strength is attained.

Signed by me, this 3rd day of Oct., 1917.
EDWARD A. TAYLOR.
